RAILWAY SIGNALING APPARATUS.

Bernard E. O'Hagan, Swissvale, Pa., assignor to
The Union Switch & Signal Company, Swiss-
vale, Pa., a corporation of Pennsylvania

Application June 27, 1939, Serial No. 281,373

12 Claims. (Cl. 246—34)

My invention relates to railway signaling apparatus, and has particular reference to apparatus of the type employed in railway signaling systems in which coded trackway energy is utilized to control either or both wayside signals and train-carried cab signals.

It has hitherto been proposed to employ relays of the saturation type as code following relays in connection with signaling systems utilizing coded trackway energy. I have found that when saturation type code following relays are so employed, the energy which is caused to be reproduced in the saturation relays in response to the coded trackway energy might not correspond to such trackway energy, due to the fact that saturation type relays have, as a general rule, a residual output during the interval that the saturation relay is controlled to have its minimum output. This causes the saturation relays to have a relatively low amplification ratio, or in other words, the ratio of the maximum output of such relays to their minimum output is relatively small. As a result of the above condition, systems employing such relays might have somewhat limited efficiency in operation. Accordingly, an object of my present invention is the provision of a novel and improved type of saturation relay having a relatively high amplification factor.

Another object is to effect the improvement in the amplifying ratio of such relays by decreasing the minimum or residual output of such relays.

A further object is to effect the above reduction in residual output of saturation relays by simple and economical means, which requires a minimum of apparatus and expenditure of energy.

Other objects and advantages of my invention will appear as the specification progresses.

I shall describe one form of apparatus embodying my invention, and shall then point out the novel features thereof in claims.

The accompanying drawing is a diagrammatic view showing a preferred form of apparatus embodying my invention as applied to a coded track circuit for a railway signaling system. In the particular embodiment of my invention represented in the drawing, apparatus embodying my invention is illustrated as being utilized at a cut-section location in a track section to cascade track circuit current from one subsection into the next. The use of a saturable transformer in this manner is disclosed and broadly claimed in a copending application for Letters Patent, Serial No. 280,731, filed on June 23, 1939, by Claude M. Hines, for Railway signaling apparatus.

55 Referring to the drawing, the reference char-

acter DR designates a novel and improved type of relay of what I shall term the saturation type. As here shown, relay DR comprises a ladder shaped magnetizable core 3, having five parallel legs 4, 5, 6, 7, and 8 connected together at each end to form an integral relay core structure. The central leg 6 of the core is provided with a primary or local input winding 11 constantly connected to a source of periodically varying current, preferably a source of alternating current (such as a generator not shown in the drawing) having its terminals designated by the reference characters BX and CX, for setting up a primary flux in core 3. As is readily apparent from an inspection of the drawing, the primary flux set up by winding 11 is provided with two magnetic circuits through the relay core, one circuit of which I shall term a main circuit, and the other circuit of which I shall term a leakage circuit. The main magnetic circuit of core 3 comprises the common leg 6, the two core legs 7 and 8 in parallel, and the adjacent top and bottom portions of the core. The leakage magnetic circuit comprises the common leg 6, the two core legs 4 and 5 in parallel, and the adjoining top and bottom portions of the core. Both circuits, therefore, have a common leg 6 of the core and each circuit is provided with two parallel paths. The relative dimensions or cross sections of the core elements forming the two magnetic circuits are selected and so proportioned that under no load conditions, the circuits have substantially equal reluctances so that the primary flux divides equally between the two circuits.

The main magnetic circuit of core 3 is provided with a secondary winding 12 which comprises two coils 12a and 12b disposed respectively on the two parallel paths 7 and 8 of the main circuit, and which coils are connected in series in such manner that any electromotive forces induced therein in response to flux flowing in the same directions in the legs are additive. The leakage magnetic circuit of core 3 is provided with two biasing coils 13 and 14 disposed respectively on the two parallel paths 4 and 5 of the circuit, each of the coils 13 and 14 being short-circuited by an asymmetrical unit designated by the reference character 15 or 16, as the case may be, whereby unidirectional current only is permitted to flow in the coils. The coils 13 and 14 are each effective normally to increase the reluctance of its associated path in the leakage circuit of the core, by supplying thereto unidirectional flux in response to the unidirectional current induced in the coils by the primary flux.

- supplied from winding 11. The coils 13 and 14 and their associated asymmetrical units 15 and 16 are so arranged as to send flux through legs 4 and 5 in opposite directions, as indicated by the arrows shown in the diagram; or in other words, to act cumulatively to send flux around in a local magnetic circuit which includes the legs 4 and 5 and the adjoining top and bottom portions of the core.
- With relay DR constructed and arranged in the manner thus far described, it is apparent that the increase in reluctance of the leakage circuit effected by the short circuited coils 13 and 14 normally causes the greater portion of the primary flux to be circulated through the main circuit whereby normally a relatively high electromotive force is induced in secondary winding 12.
- Relay DR further is provided with a saturation winding 17, which winding comprises four coils 17a, 17b, 17c and 17d disposed respectively on legs 4, 5, 7 and 8 of the relay core 3. The pairs of coils 17a and 17b, which are disposed on the two parallel paths 4 and 5 of the leakage circuit, are connected in series in such manner that the resultant of the electromotive forces normally induced therein by the alternating primary flux is substantially zero, and the other pair of coils 17c and 17d, which are disposed on the two parallel paths 7 and 8 of the main circuit, also are connected in series in such manner that the resultant of the electromotive forces normally induced therein by the alternating primary flux is substantially zero. The pairs of coils of the saturation winding disposed on the main and on the leakage circuits are connected in series across the terminals of a source of unidirectional current, such, for example, as a rectifier R, which rectifier has its output terminals connected to winding 17 and has its input terminals connected to a source of alternating current. The polarity and magnitude of the current supplied from rectifier R to winding 17 is such that when the winding is energized, the coils 17c and 17d act cumulatively to send a saturating flux around in a local magnetic circuit comprising the two parallel paths 7 and 8 and the adjoining top and bottom portion of the core forming a portion of the main magnetic circuit, whereby the reluctance of that portion of the main circuit is increased to a value such as to substantially magnetically saturate that portion of the core. Under the above condition (winding 17 supplied with unidirectional current) the two coils 17a and 17b act cumulatively to circulate a flux around in the local magnetic circuit formed in the leakage circuit by the legs 4 and 5, in opposition to the flux circulated therein by biasing coils 13 and 14, whereby the two opposing fluxes tend to neutralize each other so that as a result the normal reluctance of the leakage circuit is decreased. It can be seen, therefore, that when winding 17 is supplied with unidirectional current of the above mentioned polarity and magnitude, the primary flux then is caused to circulate through the leakage circuit by virtue of the relative differences in reluctances of the two circuits of the core, whereby the magnitude of the electromotive force induced at this time in winding 12 of the relay is very small and approaches a zero value. It follows that a relatively high electromotive force is induced in winding 12 when winding 17 is deenergized, and that a relatively low electromotive force is induced in winding 12 when winding 17 is energized, or in other words, that a relatively high electromotive force

is or is not induced in output winding 12 of relay DR according as the control winding of the relay is not or is energized.

From the foregoing, it is readily apparent that relay DR functions as a "back contact" type saturation relay, in that maximum energy is induced in and supplied from the secondary or output winding of the relay only when the control winding of the relay is deenergized, thereby corresponding in operation to a back contact of a tractive armature type relay, which contact is controlled to a circuit closing position only when the control winding of the armature type relay is deenergized. It will be understood, of course, that relay DR may be constructed as a "front contact" type saturation relay by mounting the secondary winding 12 on legs 4 and 5 of the leakage circuit, in which event, of course, maximum output will be obtained from the relay when control winding 17 is energized. Also, separate secondary windings may be provided on each of the two magnetic circuits of the core, thereby providing a saturation type relay having "front contact" and "back contact" secondary windings.

A saturation relay constructed in accordance with my invention may be advantageously utilized as a code following relay in connection with coded track circuits of the type employed in railway signaling systems. In the drawing is shown one such application, in which a "back contact" type saturation relay embodying my invention is positioned at a cut section location in a track section for cascading trackway energy from one portion of the section to the next adjoining portion of the section.

The typical coded track circuit shown in the drawing comprises the track rails 18 and 18a of a stretch of railway track electrically separated into a track section E—F by means of the usual insulated rail joints 19, and which section E—F is divided by insulated joints 19 located at a cut section location Ea in the section, into an advance subsection E—Ea and a rear subsection Ea—F.

The particular track circuit illustrated is adapted for use with a railway signaling system for a railway employing electrical propulsion, in which system the track rails 18 and 18a form a portion of the return circuit of the propulsion current. Section E—F, therefore, is shown provided with impedance bonds 20, one for each set of insulation joints 19, and which bonds in the usual form permit the transfer of propulsion current around insulation joints 19 but which prevent a similar transfer of trackway signaling current. It is to be understood, of course, that a relay embodying my invention is equally well suited for use in connection with coded track circuits applied to a steam road, in which latter application the impedance bonds 20 would, of course, be omitted. In connection with a steam road, also, the resonant transformer units RU later to be referred to may be replaced by the usual form of relay transformer.

The rails of section E—F are supplied with coded trackway signaling energy in the usual manner through the medium of the track transformer TT, which transformer has its secondary winding connected across the track rails of the section at its exit end E, and has its primary winding connected to a source of current (preferably a source of alternating current having its terminals designated in the drawing by the reference characters BX and CX) over a contact governed by a coding device CT, which device is

constantly energized and constantly opens and closes its coding contact a predetermined number of times per minute. It will be understood, of course, that the apparatus supplying trackway energy to section E—F may, if so desired, be governed by traffic conditions in advance of the section through the medium of control apparatus of the well-known form (not shown in the drawing) and that the trackway energy may be coded at any one of a plurality of codes for selectively controlling a multiple indication traffic controlling signal.

The coded track circuit further comprises a code responsive relay TR, which receives energy from the track rails of the section at its entrance end through the medium of a resonant transformer unit RU!, which unit is effective to transfer the trackway signaling energy from the rails of the section to the associated code following relay, but which unit prevents the transfer of the electric propulsion current to the relay. The code responsive track relay TR, may be, as shown, a code following relay of the tractive armature type, or may be if desired a code following relay 25 of the saturation type, such as for example, as is shown in my copending application for Letters Patent, Serial No. 280,997, filed on June 24, 1939, for Railway signaling apparatus.

The track circuit for section E—F, as shown, further is provided at the cut-section location Ea of the section with a saturation type relay DR embodying my present invention, and which relay cascades trackway energy from the advance subsection E—Ea into the rear subsection Ea—F in the following manner. Relay DR is arranged at location Ea with its secondary winding 12 connected across the track rails of rear subsection Ea—F and with its saturation winding 11 receiving energy from the rails of the subsection E—Ea through the medium of a resonant transformer unit RU (located at Ea) and rectifier R, which supplies unidirectional impulses of energy from the track rails of section E—Ea to relay DR. The magnitude and polarity of current supplied by transformer unit RU and rectifier R to relay DR are such that the unidirectional impulses supplied to winding 11 cause the two parallel paths 1 and 2 of the main circuit of the relay DR to become magnetically saturated, and also cause a decrease in the reluctance of the parallel paths 4 and 5 of the leakage circuit of the relay. Relay DR, therefore, functions in the manner previously described to cause a relatively high electromotive force to be induced in secondary winding 12 of the relay when winding 11 of the relay is deenergized (as for example during the "off" period of the coded trackway energy of subsection E—Ea), and causes the electromotive force induced in winding 12 to drop to substantially a zero value when winding 11 is energized (during the "on" period of the code).

It is readily apparent from the foregoing that the trackway energy supplied to subsection E—Ea is reproduced in kind by relay DR and is supplied to subsection Ea—F, whereby the trackway energy of the advance subsection is cascaded around the insulated joints 19 located at Ea into the rear subsection, so that section E—F is provided with coded trackway energy throughout its entire length in the same manner as if the rails of the section were continuous conductors from one end of the section to the other.

It should be noted that relay DR, being of the "back contact" type saturation relay, also is effective to supply steady or non-coded "clearing

out" energy to rear subsection Ea—F when a train occupies only subsection E—Ea, this steady energy being supplied rear subsection Ea—F by virtue of the fact that a train occupying subsection E—Ea shunts control winding 17 of relay DR, thereby causing the electromotive force induced in output winding 12 of relay DR and supplied to subsection Ea—F to be at its maximum value. This steady "clearing out" energy may be utilized to control apparatus of the well-known form (usually located adjacent the entrance end of the section but not shown in the drawing) which is desired to be responsive only to traffic conditions in subsection Ea—F.

An advantage of a saturation relay constructed in accordance with my present invention is that the residual or minimum output of such relay is substantially zero. The ratio of the maximum output of the relay to its substantially zero minimum output accordingly is relatively large, with the result that a saturation relay embodying my invention has an amplification factor which substantially corresponds to the amplification factor possessed by tractive armature type relays.

Another advantage is that a relay embodying my present invention is particularly well adapted for use as a code following relay in connection with a control circuit which is supplied with coded energy having "on" periods wherein energy is supplied to the circuit and "off" periods wherein energy is not supplied. When so employed, a relay embodying my invention reproduces the coded energy and supplies from its output winding coded energy having "on" periods during which maximum output is supplied from the relay and "off" periods during which substantially no energy is supplied. The coded energy produced by such relay accordingly corresponds to the form of coded energy supplied by the control circuit to the relay control winding, with the result that the saturation relay functions substantially in the same manner as a tractive armature type code following relay. Thus, for example, when a saturation relay embodying my invention is employed as a code following relay in cut-section facilities, the coded trackway energy supplied by such relay to the rails of the rear subsection has substantially the same characteristics as is possessed by the coded trackway energy supplied to the advance subsection. Improved operation of the code following and decoding apparatus of the section accordingly is effected, since there is no residual output supplied to the rails of the rear subsection during the "off" period of the code, and as a result the code responsive apparatus is fully deenergized and is not improperly partially energized during the "off" period of the trackway energy.

Although I have herein shown and described only one form of railway signaling apparatus embodying my invention, it is understood that various changes and modifications may be made therein within the scope of the appended claims without departing from the spirit and scope of my invention.

Having thus described my invention, what I claim is:

1. In combination, a relay of the saturation type comprising a magnetizable core having two magnetic circuits arranged in shunt to each other, said relay having a primary winding disposed on said core for setting up a primary flux in both of said two magnetic circuits when supplied with periodically varying current, said relay having biasing means disposed on a particu- 75

lar one of said two magnetic circuits and responsive to the primary flux to set up a unidirectional biasing flux of a particular polarity in said particular one magnetic circuit whereby the reluctance of that magnetic circuit normally is relatively high with respect to the reluctance of the other of said two magnetic circuits, said relay having a saturation winding comprising two portions one disposed on said particular one magnetic circuit and effective when supplied with unidirectional current of a preselected polarity to set up a saturation flux in opposition to said biasing flux whereby the reluctance of said particular one magnetic circuit is decreased, the other portion of said saturation winding being disposed on said other magnetic circuit and being effective when supplied with current to set up a saturation flux whereby the reluctance of said other magnetic circuit is increased to a value relatively high with respect to the reluctance of said particular one magnetic circuit, said relay also having a secondary winding disposed on one of said two magnetic circuits whereby the magnitude of the electromotive forces induced therein by the primary flux of the relay is controlled by the flux due to current in said saturation winding in step with the supply of coded current to said saturation winding, means for constantly supplying periodically varying current to said primary winding of said relay, and means for supplying coded unidirectional current of said preselected polarity to said saturation winding of said relay.

2. The combination with a magnetizable core having two magnetic circuits arranged in shunt to each other and both supplied with a primary flux from a primary winding disposed on said core and constantly connected with a source of periodically varying current, of biasing means disposed on a particular one of the two magnetic circuits of the core and responsive to the primary flux to supply a biasing flux to said particular one magnetic circuit whereby the reluctance of that magnetic circuit normally is caused to be relatively high with respect to the reluctance of the other of the two magnetic circuits of the core, a control circuit supplied with current from a source of periodically interrupted or coded current, a saturation winding receiving unidirectional current of a preselected polarity from said control circuit and comprising two portions one disposed on said particular one magnetic circuit and effective when supplied with said unidirectional current to supply a saturating flux to said particular one magnetic circuit in opposition to said biasing flux whereby the reluctance of that magnetic circuit is decreased, the other portion of said saturation winding being disposed on said other magnetic circuit and being effective when supplied with said unidirectional current to supply a saturating flux to said other magnetic circuit whereby the reluctance of that magnetic circuit is caused to be increased to a value relatively high with respect to the reluctance of said particular one magnetic circuit, and a secondary winding disposed on one of the two magnetic circuits of the core whereby the magnitude of the electromotive forces induced therein by the primary flux of the core is controlled in step with the supply of unidirectional current to said saturation winding from said control circuit.

3. The combination in a relay of the saturation type having a primary winding normally supplied with periodically varying current for setting up a primary flux in both of two magnetic

circuits and a secondary winding disposed on one of the two magnetic circuits, of means disposed on a particular one of the two magnetic circuits and responsive to the primary flux for setting up a biasing flux in said particular one magnetic circuit whereby the reluctance of that magnetic circuit normally is caused to be relatively high with respect to the reluctance of the other of the two magnetic circuits, a saturation winding having two portions one disposed on each of the two magnetic circuits in such manner that when said saturation winding is supplied with unidirectional current of a preselected polarity a saturating flux is set up in each of the two magnetic circuits whereby the reluctance of said particular one magnetic circuit is reduced and the reluctance of said other magnetic circuit is increased, and means for at times supplying said saturation winding with unidirectional current of said preselected polarity.

4. The combination in a relay of the saturation type having a primary winding normally supplied with periodically varying current for setting up a primary flux in both of two magnetic circuits and a secondary winding disposed on a particular one of the two magnetic circuits, of means disposed on the other of the two magnetic circuits and responsive to the primary flux for setting up a biasing flux in said other magnetic circuit whereby the reluctance of that magnetic circuit normally is caused to be relatively high with respect to the reluctance of said one magnetic circuit and an electromotive force of relatively large magnitude is caused to be induced in the secondary winding by the primary flux, a saturation winding having two portions one disposed on each of the two magnetic circuits in such manner that when said winding is supplied with unidirectional current of a preselected polarity a saturating flux is set up in each of the two magnetic circuits whereby the reluctance of said other magnetic circuit is reduced and the reluctance of said one magnetic circuit is increased to cause an electromotive force of relatively small magnitude to be induced by the primary flux in the secondary winding, and means for at times supplying said saturation winding with unidirectional current of said preselected polarity.

5. In a relay of the saturation type having a primary winding normally supplied with periodically varying current for setting up a primary flux in both of two magnetic circuits and a secondary winding disposed on one of the two magnetic circuits, a biasing winding disposed on a particular one of the two magnetic circuits and short-circuited through an asymmetrical unit normally to increase the reluctance of said particular one magnetic circuit by supplying a biasing flux thereto in response to the primary flux, a saturation winding having two portions one disposed on said particular one magnetic circuit and the other disposed on the other of the two magnetic circuits, said one portion of the saturation winding being effective when supplied with unidirectional current of a predetermined magnitude and polarity to decrease the reluctance of said particular one magnetic circuit by supplying a saturating flux thereto in opposition to the biasing flux created by said biasing winding and said other portion of the saturation winding being effective when supplied with said unidirectional current to increase the reluctance of said other magnetic circuit by supplying a saturating flux thereto, and means for supplying said satu-

ration winding with unidirectional current of said predetermined magnitude and polarity.

6. A relay of the saturation type comprising an input winding normally supplied with periodically varying current, two magnetic circuits for said relay both having a portion in common linked by said input winding, a secondary winding disposed on one of said two circuits, a coil short-circuited by an asymmetrical unit disposed on the other of said two circuits for increasing normally the reluctance of that circuit, a saturation winding having one portion disposed on said one circuit and another portion disposed on said other circuit, said one portion being effective when supplied with unidirectional current of a predetermined magnitude and polarity to increase the reluctance of said one circuit and said other portion of said saturation winding being effective when supplied with said unidirectional current to decrease the reluctance of said other circuit by supplying flux thereto in opposition to the flux created by said short-circuited coil, and means for supplying said saturation winding with unidirectional current of said predetermined magnitude and polarity.

7. A relay of the saturation type comprising, in combination, a magnetizable core having two magnetic circuits each having two parallel paths, a primary winding linking both of said two magnetic circuits and normally being supplied with periodically varying current, two biasing coils one disposed on each of the two parallel paths of a particular one of said two magnetic circuits, said two biasing coils each being short-circuited by an asymmetrical unit and said two coils cooperating to circulate a flux through a local magnetic circuit formed by the two parallel paths of said particular one magnetic circuit to normally increase the reluctance of said particular one magnetic circuit, a secondary winding comprising two coils one disposed on each of the two parallel paths of one of said two magnetic circuits and said two coils being connected in series in such manner that any voltages induced therein in response to flux flowing in the same directions through each path are additive, a saturation winding comprising four coils one disposed on each of the parallel paths of said two magnetic circuits and said coils being connected in series in such manner that when said saturation winding is supplied with unidirectional current of a predetermined value one pair of coils disposed on said particular one of said magnetic circuits cooperate to circulate a flux through the two parallel paths of said particular one circuit in opposition to the flux circulated therein by said short-circuited biasing coils to thereby reduce the reluctance of said particular one magnetic circuit and the other pair of coils disposed on the other magnetic circuit of the core cooperate to circulate a flux through the two parallel paths of that circuit to substantially magnetically saturate said other magnetic circuit, and means for supplying unidirectional current of said predetermined value to said saturation winding.

8. A relay of the saturation type comprising, in combination, a magnetizable core having two magnetic circuits each having two parallel paths, a primary winding linking both of said two magnetic circuits, said primary winding normally being supplied with periodically varying current for setting up a primary flux in said core, a secondary winding comprising two coils one disposed on each of the two parallel paths of one of said magnetic circuits, said coils of the secondary

winding being connected in series in such manner that any voltages induced therein in response to said primary flux are additive, two other coils one disposed on each of the two parallel paths of the other of said two magnetic circuits, each of said other coils being short-circuited by an asymmetrical unit and said two other coils cooperating to circulate a flux through a local magnetic circuit formed by the two parallel paths of said other circuit to increase the reluctance of said other magnetic circuit whereby the primary flux is normally circulated through said one magnetic circuit to cause a relatively high electromotive force to be induced in said secondary winding in response to said primary flux, a saturation winding comprising four coils one disposed on each of the parallel paths of said two magnetic circuits, said four coils of the saturation winding being connected in series in such manner that when said saturation winding is supplied with unidirectional current of a predetermined value one pair of coils disposed on the two parallel paths of said one magnetic circuit cooperate to circulate a saturating flux through a local magnetic circuit formed by such two parallel paths to magnetically saturate said one magnetic circuit and the other pair of coils disposed on the two parallel paths of said other magnetic circuit cooperate to circulate a flux through the local magnetic circuit formed by the two parallel legs of said other magnetic circuit in opposition to the flux circulated therein by said two other coils, whereby the reluctance of said other magnetic circuit is decreased, and means for supplying said saturation winding with unidirectional current of said predetermined value.

9. A relay of the saturation type comprising, in combination, a magnetizable core having two magnetic circuits each having two parallel paths, a primary winding linking both of said magnetic circuits, said primary winding normally being supplied with periodically varying current for setting up a primary flux in said core, a secondary winding comprising two coils one disposed on each of the two parallel paths of one of said magnetic circuits, said coils of the secondary winding being connected in series in such manner that any voltages induced therein by said primary flux are additive, two biasing coils one disposed on each of the two parallel paths of the other of said magnetic circuits, each of said biasing coils being short-circuited by an asymmetrical unit and being normally effective to supply a flux to said other magnetic circuit which increases the reluctance of that magnetic circuit whereby the primary flux supplied by said primary winding is circulated through said one magnetic circuit to induce a relatively high electromotive force in said secondary winding, a saturation winding comprising four coils one disposed on each of the parallel paths of said two magnetic circuits, said four coils of the saturation winding being connected in series in such manner that the electromotive forces normally induced in the pair of coils disposed on each of said magnetic circuits in response to said primary flux is substantially zero, and means for at times supplying said saturation winding with unidirectional current of a predetermined value whereby unidirectional flux is supplied to said one magnetic circuit to magnetically saturate that circuit and unidirectional flux is supplied to the other magnetic circuit in opposition to the flux created by said biasing coils to reduce the reluctance of said other circuit.

10. In a signaling system for railroads, the combination with a section of railway track electrically separated by insulated rail joints into adjoining advance and rear subsections and having means for supplying coded trackway energy to the rails of said advance subsection, of a code following relay of the saturation type comprising a magnetizable core having the usual primary and secondary windings and having 10 duplicate parallel core portions which form a shunt for the main magnetic circuit coupling the primary and secondary windings, each of the duplicate parallel core portions being provided with a coil short-circuited by an asymmetrical unit and effective when said primary winding is supplied with periodically varying current to increase the reluctance of said parallel core portions whereby the primary flux created by said primary winding is circulated through said main magnetic circuit to induce in said secondary winding a relatively high electromotive force, said relay also being provided with a saturation winding having one portion disposed on the main magnetic circuit and another portion disposed on said parallel core 25 portions, said one portion of the saturation winding being effective when supplied with unidirectional current of a predetermined value to magnetically saturate said main magnetic circuit, said other portion of the saturation winding being effective when supplied with said unidirectional current to decrease the reluctance of said parallel core portions by supplying flux thereto in opposition to the flux created by said short-circuited coils, whereby when said saturation winding is energized by said unidirectional current the primary flux is shunted from said main magnetic circuit and a relatively low electromotive force is induced in said secondary winding, means for 30 constantly supplying periodically varying current to said primary winding, means for supplying said saturation winding with unidirectional current of said predetermined value from said advance subsection, and means for connecting said secondary 35 winding to said rear subsection whereby that subsection is supplied with trackway energy in re-

sponse to the trackway energy supplied from said advance subsection to said saturation winding.

11. In combination, a magnetizable core having two magnetic circuits, a primary winding disposed on said core and connected with a source of alternating current for setting up a primary flux in each of said two circuits, means disposed on one of said circuits and responsive to said primary flux traversing such circuit for normally increasing the reluctance of that circuit to force the major portion of said primary flux through the other magnetic circuit, an output winding disposed on said other magnetic circuit, a control winding having two portions one disposed on each of said two magnetic circuits, and means for supplying to said control winding unidirectional energy of a preselected magnitude and polarity for increasing the reluctance of said other magnetic circuit and for decreasing the reluctance of said one magnetic circuit whereby to shunt the major portion of said primary flux away from said other magnetic circuit.

12. In combination, a magnetizable core having a primary and a secondary winding disposed on a main magnetic circuit and also having a portion of said core arranged to shunt flux due to current in said primary winding away from said secondary winding, means for constantly supplying said primary winding with alternating current, a coil short-circuited through an asymmetrical unit disposed on the shunt portion of said core for normally increasing the reluctance of that portion to force the flux due to current in said primary winding through the main magnetic circuit, a control winding having two portions one disposed on the main magnetic circuit and the other disposed on the shunt portion of said core, and means for supplying to said control winding unidirectional current of a preselected magnitude and polarity for increasing the reluctance of said main magnetic circuit and for decreasing the reluctance of said shunt portion of the core whereby to shunt the major portion of the flux due to current in said primary winding away from said main magnetic circuit.
